UNITED STATES PATENT OFFICE.

ARTHUR C. ROWLEY, OF PHILADELPHIA, PENNSYLVANIA, ASSIGNOR TO GLOBE AUTOMATIC SPRINKLER COMPANY, OF PHILADELPHIA, PENNSYLVANIA, A CORPORATION OF PENNSYLVANIA.

DRY-PIPE ACCELERATOR.

1,378,805.

Specification of Letters Patent. Patented May 17, 1921.

Application filed June 11, 1920. Serial No. 388,336.

To all whom it may concern:

Be it known that I, ARTHUR C. ROWLEY, a citizen of the United States, residing in Philadelphia, Pennsylvania, have invented 5 Dry-Pipe Accelerators, of which the following is a specification.

This invention relates to apparatus for hastening the delivery of water to an automatic fire extinguishing system, after the 10 opening of one or more of the sprinkler heads thereof, and one object of said invention is to provide an apparatus which shall reduce to a minimum the time elapsing between the reduction of air pressure in the 15 system resulting from the opening of a sprinkler head, and the time when the dry pipe valve operates to permit flow of water under pressure into said system.

My invention further contemplates a novel 20 device of the general type above indicated, particularly designed to respond to a relatively slight reduction in air pressure, which shall be certain in action and not liable to get out of order, the arrangement being 25 such that the parts are self restoring to their set positions after operation.

Another object of my invention is to provide an accelerator designed for use in connection with a dry pipe valve, whose parts 30 shall be so arranged as to automatically establish communication between the sprinkler system and the intermediate chamber of the dry pipe valve in a minimum time after there has been a reduction of air pressure in said system such as would be caused 35 by the opening of a sprinkler head.

These objects and other advantageous ends 40 I attain as hereinafter set forth, reference being had to the accompanying drawings, in which,

Figure 1 is a side elevation illustrating my invention as applied to a dry pipe valve;

Fig. 2 is a vertical section on the line 2—2, Fig. 1, drawn on a larger scale than said figure;

Fig. 3 is a side elevation of a portion of Fig. 2, part of the main casing being broken away to illustrate the detail construction of the parts; and

50 Fig. 4 is a horizontal section on the line 4—4, Fig. 2.

In the drawings, 1 represents the casing of a differential dry pipe valve assembly,

the same being divided into two chambers 1^a and 6, the former having its upper end 55 connected to a conduit 3, constituting the riser leading to or forming part of the air containing portion of a sprinkler system, and the chamber 6 having its lower end connected to a conduit 2 leading from a source 60 of water under pressure, the two chambers being divided by a partition 1^b having an opening 1^c therein permitting communication between the two chambers. The inlet from the conduit 2 into the intermediate 65 chamber 6 is normally closed by a water clapper or valve 4, and the opening 1^c is normally closed by an air clapper or valve 5 connected to the valve 4 by means of a suitable link connection 5^a, so that the two 70 valves 4 and 5 will operate in unison. The chamber 6 is normally maintained at atmospheric pressure by a drip passage of 75 relatively small cross section (not shown).

The water from the supply system exerts 80 a relatively high pressure on a relatively small area provided by the under side of the valve 4, and the air under a considerably lower pressure in the sprinkler system similarly acts on the relatively large area provided by the upper face of the valve 5, which through the connecting mechanism, is designed to normally hold said valve 4 closed against the water pressure.

Obviously when a sprinkler head opens 85 in the system of which the pipe or riser 3 forms a part, it is highly desirable that water from the conduit 2 shall be delivered to said system at the earliest possible moment, and my invention is particularly designed to accelerate the opening of the valve 5 by the introduction to the intermediate chamber 6 of air under pressure, which shall act to hasten the release and opening of the valve 4. For this purpose I mount adjacent 95 the dry pipe valve a casing preferably made in three parts, 7, 8 and 9 of which the first is connected through a conduit 10 with the intermediate chamber 6 of said valve.

In the bottom 12 of the first section 7 is 100 a passage in which is a valve seat designed to coact with a vertically guided valve 13, and between the sections 7 and 8 is mounted a structure 14 having a central opening for the passage and guidance of a stem 15 105 whereby the valve 13 is operatively con-

nected to a relatively heavy float 16, vertically movable in a chamber 24 of the casing section 8.

The section 8, in addition to the chamber 24 for the float 16, has to one side of the same a second chamber 17 whose upper portion is connected through a pipe 18 with the upper part of the chamber 24, and said conduit has also connected to it a branch 20 leading to the upper chamber of the dry pipe valve or to that part of the system in which is confined the air whose pressure is released or reduced by the opening of a sprinkler head. The connection between the conduits 18 and 20 is such that while the latter has free communication with the chamber 24, it can communicate with the chamber 17 only through a relatively restricted opening preferably formed in an element 21 connected in said conduit 20, so that while the air under pressure from the upper part of the dry pipe valve or riser 3 may rapidly flow in large volume into the chamber 24, it can flow at but a relatively slow rate into the chamber 17.

Said chamber 17, through an opening 22, is in free communication with the interior of a relatively large chamber 23 provided by the section 9 of the casing, and the chamber 24 has connected to its lowest portion one branch 25 of a U-shaped conduit, whose second branch 26 extends vertically upward into the chamber 17 to a height above the level of the bottom of the chamber 24.

This second branch 26 is preferably provided with a bottom valve seat 28 and a top valve seat 29 for a check valve 30 in the form of a glass or relatively light metal ball, and the conduit 25—26 normally contains a body of mercury or equivalent liquid which extends to a level slightly below the bottom of the float or weight 16, when this occupies its lowest position with the valve 13 resting upon and closing the seat in the passage 11. The lower end of the chamber 23 has an opening normally closed by a plug 31 held in place by a conveniently removable clamp 32.

With the above described arrangement of parts, the two clappers or valves 4 and 5 of the dry pipe valve are normally closed and the ball 30 rests upon the top surface of the mercury in the branch 26. The air under pressure from the sprinkler system supplied through the pipe 20, fills the chambers 17 and 23 as well as the chamber 24, while the chamber of the casing section 7 is at atmospheric pressure;—the passage of air from the chamber 24 to this latter chamber being prevented by the valve 13 which is held seated by the float 16.

If now there is such a reduction of the air pressure in the riser 3 as would be caused by the opening of a sprinkler head, a corresponding reduction of air pressure occurs at once in the chamber 24, owing to the con-

nection provided by the pipes 18 and 20, between this chamber and said riser. Since however the container or tank provided by the chambers 23 and 17 is filled with air at the relatively high pressure normally existing in the riser, the expansion of this air acts upon the mercury in the branch 26 of the U-tube and forces it into the chamber 24 as soon as there is a relatively slight reduction of the air pressure therein. As a result of the rise of mercury in this latter chamber, the float 16 is buoyed up and rises, opening the valve 13 and permitting free flow of air from the riser 3 through the pipes 20 and 18, into the chamber 24 through the passage 11 and pipe 10, into the intermediate chamber 6 of the dry pipe valve.

The sudden rise of pressure in said intermediate chamber at once unseats the air clapper 5 and hastens the release and opening of the water clapper 4, so that in a typical case water is supplied to the sprinkler system when the air pressure therein has fallen three pounds below normal, instead of being withheld until such pressure had fallen ten pounds or more.

The above action, occurring by reason of the expansion of the air in the chambers 17 and 23, results from the fact that said air cannot escape in any material amount through the restricted opening in the fitting 21, and the discharge of all of the mercury from the U tube 25—26 is prevented by the valve 30 engaging the lower seat 28. Should there be a return flow of water from the dry pipe valve through the pipe 10 into the section 7 and chamber 24, such as might force the mercury in the U-tube toward the chamber 17, the escape of said mercury from the branch 26 is prevented by the valve 30 engaging its topmost seat 29. Obviously when the flow of water through the dry pipe valve ceases and the system is restored to its normal condition the mercury in the pipe 25—26 returns to its normal level, preferably just below the bottom of said weight, and the valve 13 is automatically seated by the float 16.

One advantage of the above described construction resides in the fact that there must be an actual flow of air from the system, such as would occur by reason of the opening of a sprinkler head, since the device will not operate if the air pressure is reduced by a mere gradual leakage. Owing to the fact that the dry pipe valve is caused to function when the pressure in the system has been reduced by but a relatively small amount, it is obvious that water is delivered to an open sprinkler head in a much shorter time than would ordinarily be possible.

I claim:—

1. An accelerator consisting of a valve controlling the flow of air under pressure to the intermediate chamber of a dry pipe

- valve; a float for operating said controlling valve; a body of liquid; and means for causing said liquid to act on the float to open said valve when a reduction of the air pressure occurs in the air chamber of the dry pipe valve.
2. An accelerator consisting of a valve controlling flow of air under pressure to the intermediate chamber of a dry pipe valve; an air container connected to the air chamber of the dry pipe valve; and a liquid operated device actuated by the expansion of the air in said container when the pressure falls in the dry pipe valve, for causing opening of the air controlling valve and the delivery of air under pressure to the intermediate chamber of the dry pipe valve.
3. An accelerator consisting of a valve controlling flow of air under pressure to the intermediate chamber of a dry pipe valve; a float chamber; an expansion chamber; a conduit connecting said chambers; a float connected to the controlling valve and operative in the float chamber; liquid in said conduit; and a second conduit providing a relatively restricted connection between the air chamber of the dry pipe valve and said expansion chamber.
4. In an accelerator the combination of a valve controlling the flow of air under pressure from a sprinkler system to the intermediate chamber of a dry pipe valve; a weighted float normally holding said valve closed; and means for causing liquid to act on the float to open the valve when a predetermined reduction of air pressure occurs in the sprinkler system.
5. In an accelerator the combination of a valve controlling the flow of air under pressure from a sprinkler system to the intermediate chamber of a dry pipe valve; a weighted float normally holding said valve closed; with means for causing liquid to act on the float to open the valve when a predetermined reduction of air pressure occurs in the sprinkler system, consisting of an expansion chamber, a chamber for the float, and a liquid containing conduit connecting said chambers.
6. The combination in an accelerator of a casing having at least three chambers of which two are connected by a valve seated passage; a valve for said passage; a float in one of the chambers normally holding the valve closed; a conduit for connecting two of the chambers with a source of air under pressure and including a relatively restricted passage for preventing rapid flow of air from one of the chambers; a conduit connecting the latter chamber with the float chamber; and liquid in said conduit for acting on the float to open the valve when different pressures exist in said two chambers.
7. The combination of a differential dry pipe valve; a casing having three chambers
- of which one is connected to the intermediate chamber of said valve; a float in the second chamber of the casing; a valve controlled by said float for controlling passage of air from the float chamber to the first chamber; an expansion chamber; a liquid containing conduit connecting the float chamber and the expansion chamber; and a conduit including a relatively restricted portion for supplying air under pressure to the expansion chamber.
8. The combination in an accelerator of an expansion chamber; a float chamber adjacent thereto; a U-shaped conduit having one branch opening into the lower portion of the float chamber and a second branch opening into the expansion chamber; liquid in said conduit; a valve controlled by said float; with means for delivering air under pressure to the expansion chamber.
9. The combination in an accelerator of an expansion chamber; a float chamber adjacent thereto; a U-shaped conduit having one branch opening into the lower portion of the float chamber and a second branch opening into the expansion chamber; liquid in said conduit; a valve controlled by said float; means for delivering air under pressure to the expansion chamber; with a check valve in said U-shaped conduit mounted to prevent flow of liquid therefrom into the expansion chamber.
10. The combination in an accelerator of an expansion chamber; a float chamber adjacent thereto; a U-shaped conduit, having a branch opening into the lower portion of the float chamber and a second branch opening into the expansion chamber; liquid in said conduit; a valve controlled by said float; means for delivering air under pressure to the expansion chamber; with a check valve in said U-shaped conduit mounted to prevent more than a predetermined flow of liquid into the expansion chamber.
11. The combination in an accelerator of an expansion chamber; a float chamber adjacent thereto; a U-shaped conduit having one branch opening into the lower portion of the float chamber and a second branch opening into the expansion chamber; liquid in said conduit; a valve controlled by said float; means for delivering air under pressure to the expansion chamber; with a check valve in said U-shaped conduit arranged to prevent flow of liquid into the expansion chamber and also to limit the flow of liquid into the float chamber.
12. The combination in an accelerator of a casing having three chambers of which two are connected by a valve seated passage; a valve for said passage; a weighted float suspended from said valve for normally keeping it closed; a U-shaped conduit leading from the float chamber to the third chamber; liquid in said conduit; and a con-

duit having a relatively restricted portion for supplying air to the third chamber, while preventing its sudden escape therefrom.

5 13. An accelerator consisting of a valve controlling the flow of air under pressure to the intermediate chamber of a dry pipe valve; a float for operating said controlling valve; a body of relatively heavy liquid; 10 with means for causing said liquid to act on the float to open said valve when a reduction of the air pressure occurs in the air chamber of the dry pipe valve.

14. An accelerator consisting of a valve 15 controlling the flow of air under pressure to the intermediate chamber of a dry pipe valve; a float for operating said controlling valve; a body of mercury; and means for

causing said mercury to raise the float and open the valve when a reduction of the air 20 pressure occurs in the air chamber of the dry pipe valve.

15. The combination in an accelerator of a casing having chambers of which two are connected by a valve seated passage; a valve 25 for said passage; a weighted float in one of the chambers operative on the valve to normally keep it closed; a U-shaped conduit leading from the float chamber to the third chamber; a body of mercury in said conduit; and means for delivering air under pressure to the third chamber to cause said mercury to operate on the float and open the valve. 30

ARTHUR C. ROWLEY.
